HAMMER MILL

Merle N. Dressel, Le Sueur, Minn.

Application October 22, 1932, Serial No. 639,104
Renewed August 2, 1934

7 Claims. (Cl. 83—11)

This invention relates to an improved hammer mill for agitating and grinding granular material, especially grains, in a manner to pulverize and reduce the material to the requisite powder-like fineness.

Briefly stated, the preferred embodiment of the invention is characterized by a casing having an internal material receptacle provided with pulverizing screens of the desired gauge, together with a rotary bladed beater or agitator located in said receptacle and especially constructed to act on and condition the material in a predetermined manner.

One point of novelty is predicated upon the specific construction and shape of the casing which, as a single unit, includes an upper cylindrical portion, a lower fan housing, and an intervening conical receiver to trap and deliver the refined product into the fan housing for disposition.

The essential feature of construction is found in the rotary bladed beater regarded as novel in that it embodies a plurality of individually swingable grain crushing and pulverizing blades, believed to be superior due to their ability to prevent clogging and damage.

Other and more specific features and advantages will become more readily apparent from the following description and drawings.

30 In the drawings:

Figure 1 is a top plan view of the casing.

Figure 2 is a similar view with the hinged lids removed.

Figure 3 is a horizontal section taken approximately on the plane of the line 3—3 of Figure 4.

Figure 4 is a vertical sectional and elevational view, the section being approximately on the line 4—4 of Figure 1.

40 Figure 5 is a fragmentary detail view.

Figure 6 is a similar detail view, the section being on the line 6—6 of Figure 3.

Figure 7 is a horizontal section on the line 7—7 of Figure 4.

45 Figure 8 is a fragmentary detail of the bottom of the material receptacle.

Figure 9 is a detail view showing one of the hinged joints for mounting for the agitator blades.

50 Figure 10 is a plan view of one of the arcuate removable screens.

Figure 11 is a perspective view of one of the agitator blades.

55 Figure 12 is a top plan view of the agitator hub.

Figure 13 is an elevational view of the hub shown in Figure 12.

Figure 14 is a fragmentary plan view of a portion of the bladed agitator showing the swingable action of one of the blades.

The general assembly of parts may well be seen in Figure 4 wherein it will be observed that the part designated as the casing is generally denoted by the numeral 15. This is a sheet metal structure whose lower portion is formed into a circular fan housing 16 for the rotary suction fan 17. Incidentally this housing includes a removable base plate 18 with a detachable central bearing 19. The upper portion of the casing distinguished by the numeral 20 is of general cylindrical form and is joined to the fan housing through the medium of a conical receiver 21 into which the ground material gravitates, and from which it is cast into the fan housing. Attached to the periphery of the fan housing is a delivery duct 22 through which the material is elevated into a bin (not shown) or other depository.

The top of the cylinder 20 is composed of three parts; namely, a central stationary cross piece or spider 23 and a pair of complementary covers or lids 24 and 25 secured by hinges 26 to the part 23. The numeral 27 merely designates a filler neck or opening through which the granular material is introduced into the internal receptacle 28.

This receptacle 28 comprises a bottom disk or plate 29 formed centrally with diametrically opposed imperforate webs 30 as shown in Figure 5. On opposite sides of the webs and around its marginal portion this disk is provided with retaining channels 31 for the removable arcuate screens 32. These channels 31 extend up the ends of the webs 30, as shown in Figure 5. The screens are made removable so that they can be replaced by other screens. The screens are installed according to the particular mesh or proportions thereof depending on the fineness or consistency of the product desired. The screens cooperate with the webs in forming an endless wall for the receptacle which is disposed in spaced concentric relation to the cylinder 20. Incidentally, the numerals 33 designate spacing and supporting brackets. In addition, numerals 34 designate additional supports or braces.

The power delivery or drive shaft is distinguished by the numeral 35 and receives its power from a motor or other prime mover and this shaft extends through a bearing 36 into the conical receiver 21 and is provided on its inner end with a beveled gear 37 in constant mesh with a

companion gear 38 on the perpendicular driven shaft 39. The gears are confined in an appropriate protective housing 40 and the shafts are mounted for rotation in suitable ball bearing units 41. If desired, the shafts may be provided with power take-off pulleys 42 and 43, respectively.

The agitator comprises a centralized hollow hub 44 which is keyed to that portion of the shaft 39 located within the area of the receptacle 28. The hub is provided with circumferential vertically superposed flanges 45 to which spaced ears or lugs 46 on the inner end of the blades 47 are pivotally attached as indicated at the point 48. The agitator is sufficiently large in scope to approximately fill the receptacle 28 as illustrated in Figure 4 of the drawings. It is to be noted that the agitator blades 47 are freely pivoted and swing back and forth on their vertical axes caused by the centrifugal motion imparted thereto as the shaft 39 is set into rotation.

In practice, the material to be ground is introduced into the receptacle 28 by way of the inlet 27, the quantity being regulated according to the discretion of the operator. Obviously when the bladed agitator is set into rotation, it causes the material to whirl forcibly against the screens. The continuous centrifugal swirling and pounding action developed by this centrifugal rotating force serves to reduce the grains of material into particles susceptible of passing through the apertures in the gauging screen. The material, thus pulverized, escapes into the space between the wall of the receptacle and the cylinder 26 and gravitates into the fan housing 16 by way of the conical receiver 21. The suction action of the fan collects the pulverized material and elevates it through the duct 22 into the storage bin or other depository to which the duct 22 is connected.

It is thought that persons skilled in the art to which the invention relates will be able to obtain a clear understanding of the invention after considering the description in connection with the drawings. Therefore, a more lengthy description is regarded as unnecessary.

Minor changes in shape, size, and rearrangement of details coming within the field of invention claimed may be resorted to in actual practice, if desired.

50 I claim:

1. A hammer mill of the class described comprising a vertically arranged casing including an upper horizontally arranged cylinder, a horizontally arranged fan housing, and a conical hopper connecting said cylinder to said housing, a duct connected with the housing for delivering the pulverized product to the desired point of deposit, a vertically arranged rotary driven shaft mounted in bearings in said casing and centrally located, a fan attached to said shaft and located in said housing, a horizontally arranged receptacle in the upper portion of said casing disposed in concentric spaced relation within said cylinder, said receptacle being provided with a screened marginal rim, and a bladed agitator keyed to the upper portion of said shaft and located in said receptacle and including a hub of considerable diameter and imperforate, said agitator acting to throw the material against the screen and the particles of such material passing through the screen into the space between the receptacle and the cylinder and then passing by gravity through the hopper into the fan housing.

2. A hammer mill of the class described com-

prising a casing including a cylinder provided with closing means, a fan housing, and a conical receiver connecting the cylinder with the fan housing, a delivery duct connected to said fan housing, a perpendicular driven shaft mounted for rotation in said casing and centrally located, said shaft extending down into said housing, a fan attached to said shaft and located in the fan housing, a receptacle mounted in said cylinder and including a disk-like bottom provided with diametrically opposed upstanding imperforate webs, and on opposite sides of said webs with retaining channels of segmental form, said channels extending from an end of one web to an end of the other web and the ends of said webs having the channels formed thereon forming rightangular extensions of the first mentioned channels, removable arcuate screens mounted in said retaining channels with the ends of the screens fitting in the channels at the ends of the webs, a bladed agitator mounted on that portion of the shaft located in said receptacle, the blades of said agitator being pivoted for free swinging motion in the manner described.

3. A hammer mill comprising a casing having its upper portion fashioned to provide a cylinder, the top of said cylinder being formed with hinged lids, one of said lids having a filler opening to permit introduction of the material, the intermediate portion of the casing being fashioned to provide a conical gravity receiver, and the lower portion of the casing being formed into a circular fan housing, a duct connected with the marginal portion of the fan housing, a receptacle comprising a disk like bottom supported in the cylinder, said bottom having upstanding diametrically opposite imperforate webs, and retaining channels of segmental form, said channels extending from an end of one web to an end of the other web and the ends of said webs having the channels formed thereon forming rightangular extensions of the first mentioned channels, arcuate removable screens mounted in said retaining channels with the ends of the screens fitting in the channels at the ends of the webs, said screens cooperating with said webs in forming an endless wall for the receptacle, said wall being disposed in spaced relation to the cylinder, said casing being provided with bearings, a driven shaft mounted for rotation in said bearings, a drive shaft operatively connected with said driven shaft, a hub attached to that portion of the shaft located in the receptacle, and a plurality of radial blades pivotally attached to the hub on vertical axes, said blades sweeping through a path in close proximity to the inner surface of the wall of the receptacle.

4. A mill embodying a casing comprising a base including a horizontally disposed cylindrical drum and an inverted truncated conical portion mounted thereabove, a plate above the conical portion, a vertical shaft journaled on the base and passed upwardly through said plate, a rotor above the plate carrying peripheral hammers, a screen surrounding the hammers and cooperable therewith to reduce material, said rotor turning with the shaft, a hinged cover provided with a feed opening to enclose the rotor, a fan in the drum on the lower end of said shaft, and means to drive the vertical shaft to rotate the rotor and fan, the reduced material passing through said screen in a radially outward direction and passing down the inner side of the conical portion to the fan.

5. A mill embodying a casing comprising a base including a horizontally disposed cylindrical drum and an inverted truncated conical portion mounted thereon, a plate on the top edge
5 of the conical portion, a vertical shaft journaled on the base and passed upwardly through said plate, a rotor above the plate carrying peripheral hammers, an annular screen element on the plate surrounding the rotor and cooperating
10 with the hammers to reduce material, said plate provided with an annular opening radially outwardly of and surrounding the screen, said rotor turning with the shaft, a cover provided with a feed opening hinged to the casing to enclose
15 the rotor; a fan in the drum on the lower end of said shaft, and means to drive the vertical shaft to rotate the rotor and fan, said fan drawing the reduced material through the screen and annular opening over the conical inside surface
20 of the casing into the fan drum.

6. A mill having a fan housing enclosing a fan.

a casing above and on the housing, a horizontal stationary plate having an annular peripheral opening, said plate mounted on the casing, a cover including a feed opening over the plate to form a reducing chamber, a rotor carrying hammers in said chamber, a vertical shaft in the casing for mounting and driving the rotor, and an annular screen element carried on the plate between the periphery of the rotor and the annular peripheral opening.

7. A hammer mill embodying a casing, a vertical shaft therein, a fan housing below the casing, a horizontal fan in said housing driven by said shaft, a reducing chamber above the casing, and a rotor carrying reducing hammers in the chamber and also driven by said shaft, the casing between the chamber and housing being formed in the shape of an inverted truncated cone to direct reduced material into the center of the fan.
